PORTABLE RADIO

Morris Dweck, 442 Quentin Road,
Brooklyn, N.Y. 11223

Filed May 14, 1973, Ser. No. 359,700

Term of patent 3½ years

Int. Cl. D14—03

U.S. Cl. D56—4 B

Fig. 1

FIG. 1 is a front, top and right side perspective view of a portable radio showing my new design; and FIG. 2 is a rear, top and left side perspective view. The bottom of the radio is plain and unornamented. I claim:

The ornamental design for a portable radio, as shown.
